UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

TRANSMITTER.

1,175,048.

Specification of Letters Patent. Patented Mar. 14, 1916.

Application filed March 31, 1913. Serial No. 753,066.

To all whom it may concern:

Be it known that I, JOHN J. COMER, a citizen of the United States of America, and resident of Chicago, Cook county, Illinois, have invented a certain new and useful Improvement in Transmitters of which the following is a specification.

My invention relates to improvements in transmitters, and more particularly to transmitters comprising a granular resistance medium employed to transmit voice and musical vibrations. In transmitters of this type in which a granular resistance medium is employed, it has been found that the range of the amplitude of the vibrations to which the granular material can be subjected is very small. If the vibrations are too minute, of course the granular material is not affected sufficiently so as to give any operative results, while if the vibrations are too great the circuit is broken between the individual granules of material, thus producing a very harsh and unnatural effect. In order to maintain the vibrations within this narrow range between which the best results are obtained, recourse has heretofore been had to the method of damping the diaphragm, for example, to which the transmitter is secured. Such a method, however, has been found to be unsatisfactory, as in order to obtain the most accurate results the diaphragm or other vibrating member from which the transmitter receives its vibrations should be allowed perfectly free vibration. When the diaphragm is damped, it has the result of blotting out certain of the over-tones, thus rendering transmission imperfect.

The object of my invention is to bring the vibrations which affect the granular material into the proper range by means entirely independent of the diaphragm or vibrating member, whereby the diaphragm is left free to vibrate and is not impeded or damped. The means for controlling the vibration reside in the transmitter button itself, the vibrations being so controlled that very efficient results are obtained.

My invention is particularly adapted for use in musical transmission, whereby very delicate adjustments are required.

My transmitter is adapted to be employed with a diaphragm, as in an ordinary telephone transmitter, or can be associated di-

rectly with the sounding-board or vibrating member of a musical instrument, such as a piano or violin.

My invention will be more readily understood by having reference to the accompanying drawings, in which—

Figure 1 is an end view of a transmitter embodying the features of my invention. Fig. 2 is a sectional view taken on the line 2—2 in Fig. 1. Fig. 3 is a view partly in section, showing my invention as applied to a diaphragm in ordinary telephone work. Fig. 4 is a view showing my invention as applied to the sounding-board of a piano.

As illustrated, my transmitter comprises an inclosed casing comprising the opposing cup-shaped members 6 and 7, which are circular in form and provided with upwardly extending portions 8 and 9, which are formed so as to provide an opening 10 for filling the receptacle. Passing through the center of the members 6 and 7, which form the inclosing casing, is the stem 11 which carries the movable electrode 12. Stationary electrodes 13 and 14 are mounted on opposite sides of the casing, being carried by the disks 15 and 16, respectively, which disks are insulated from the casing. Each of these disks is provided with an opening through the central portion, 85 through which passes the stem 11. Surrounding the opening in each of these disks is an outwardly extending flange 17 threaded at its outer end. Suitable washers 18 are mounted upon these flanges, which 90 washers are insulated from the casing. Likewise, mounted upon each flange is a hollow cone-shaped member 19 lined with a felt member 20 with which an adjustable cone 21, carried by the stem 11, is adapted 95 to engage. This cone 21 is adjustable along the stem 11 by means of the nut 22 which is threaded upon the stem 11, so that by advancing the nut, the cone 21 is pressed against the felt member 20.

As illustrated, the transmitter is the same on both sides of the casing, so that by tightening upon the nuts 22 the pressure on the felt member 20 can be increased. The casing is filled with granular resistance material, such as granular carbon and fluffy asbestos placed around the stem 11 to prevent short circuiting, and the hole 10, by

which the transmitter is filled, is likewise packed with fluffy asbestos. The sides of the casing are insulated to prevent the casing itself from short circuiting the resistance material.

The transmitter as described can be attached to any suitable vibrating means, from which it is desired to transmit sound vibrations, and in Fig. 3 I have shown my invention as applied to an ordinary telephone transmitter. In this instance the stem 11 is secured to the center of the diaphragm 23.

In Fig. 4, I have shown my invention as applied to the sounding-board of a piano, in which the stem 11 is secured directly to the sounding-board 24.

In operation, assume that the device is applied as shown in Fig. 3, the diaphragm 23 receives the sound vibrations, and being undamped is free to vibrate. In order to properly control the vibrations so that they will come within the range through which the carbon material operates most efficiently, it is merely necessary to properly adjust the position of the cones 21, so as to regulate the pressure upon the felt pads or member 20. It will be seen that as illustrated the transmitter is of the inertia type—that is, the entire transmitter is moved by the vibration of the diaphragm. If the cones 21 are adjusted so that the pressure on the felt pads 20 is increased to such an extent that there is practically a solid connection between the stem 11 and the transmitter casing, the vibrations of the diaphragm will have practically no effect upon the granular material. As the nuts 22 are loosened, however, so as to decrease the pressure upon the felt pads 20, there will be a slight play or movement between the stem 11 and the casing, thus causing a slight movement of the electrode 12, which is carried by the stem, with respect to the electrodes 13 and 14 carried by the casing. In this manner, by properly regulating the tension on the felt pads 20, a very accurate adjustment can be obtained, in a very simple manner.

I find that by the use of this device I am able to bring very large vibrations down to the range at which the granular material will be most efficiently operated. Heretofore great difficulty has been experienced in taking vibrations directly off of musical instruments, due to the amplitude of the vibrations so received. This is especially true of the piano, in which the vibrations are particularly heavy. I find that I can obtain very efficient results in this manner by the use of my improved transmitter.

While I have illustrated and described one particular embodiment of my invention, and have illustrated my invention particularly in connection with a double transmitter, it is, of course, to be understood that I do not

wish to limit myself to the particular form shown and described, but that various modifications will readily suggest themselves to those skilled in the art and still come within the scope of my invention.

What I claim as my invention is:

1. In a transmitter, a movable electrode, a stem carrying said electrode, a casing carried by said stem, a vibrating member free to vibrate secured to said stem, to thereby vibrate said stem, electrode and casing, and means independent of said member for damping the vibrations of said casing with respect to said electrode.

2. In a transmitter, a granular resistance receptacle, a stem carrying an electrode associated with said receptacle, a member adapted to be vibrated to which said stem is secured, whereby a vibration of said member vibrates said electrode and receptacle, and adjustable means for damping the amount of vibration of said electrode with respect to said casing.

3. In a transmitter, a stem, a diaphragm secured to said stem, a casing carried by said stem and loosely mounted thereon, and means for adjusting the connection between said stem and casing, whereby the relative vibrations between said stem and casing can be regulated.

4. In a transmitter, a stem, a diaphragm secured thereto, a casing loosely mounted on said stem, an electrode rigidly mounted on said stem, whereby when said diaphragm is vibrated said electrode is moved relative to said casing, and means for adjusting the connection between said stem and casing to thereby regulate the movement of said electrode with respect to said casing.

5. In a transmitter, a casing, granular resistance material within said casing, a stem passing through said casing, a diaphragm carried by said stem, means for vibrating said stem, connections between said stem and casing whereby the vibrations of said stem are imparted to said casing, and means for adjusting said connections to thereby regulate the amount of movement of said stem and electrode with respect to said casing.

6. In a transmitter, a casing containing granular resistance material, a stem passing through said casing, an electrode within said casing and carried by said stem, and flexible connections between said stem and said casing whereby said stem and electrode are adapted to move relative to said casing.

7. In a transmitter, a casing containing granular resistance material, a stem passing through said casing, an electrode within said casing and carried by said stem, flexible connections between said stem and said casing whereby said stem and electrode are adapted to move relative to said casing, and means for adjusting said flexible connections

to thereby regulate the movement of said stem and electrodes with respect to said casing.

8. In a transmitter, a casing, granular resistance material in said casing, a stem passing through said casing, an electrode carried on said stem, a diaphragm secured to said stem whereby the vibration of said diaphragm is imparted to said stem and casing, an engaging member carried by said stem, a co-acting member on said casing, and a resilient medium between said member whereby the vibrations of said electrode with respect to said casing are damped.

15 9. In a transmitter, a casing, granular resistance material within said casing, a stem passing through said casing, an electrode in said casing carried by said stem, a hollow cone-shaped member on said casing surrounding said stem, and provided with a felt face, a beveled member on said stem adapted to engage said felt, and a diaphragm secured to said stem, whereby the vibrations of said diaphragm are imparted 20 to said stem and casing, the felt connection permitting movement of said stem with respect to said casing.

10. In a transmitter, a casing, granular resistance material within said casing, a stem passing through said casing, an electrode in said casing carried by said stem, a hollow cone-shaped member on said casing surrounding said stem, and provided with a felt face, a beveled member on said stem 25 adapted to engage said felt, a diaphragm secured to said stem, whereby the vibrations of said diaphragm are imparted to said stem and casing, the felt connection permitting movement of said stem with respect 30 to said casing, and means for adjusting said beveled member on said stem to thereby regulate the pressure on said felt, whereby the vibrations of said electrode with respect to said casing are adjustable.

45 11. In a transmitter, a casing, a pair of electrodes on the opposite sides of said casing, a third electrode located between the first mentioned electrodes, granular resistance material between said electrodes, a stem 50 passing through said box and carrying said

third electrode, and resilient connections between said stem and said casing, whereby a limited movement of said third electrode with respect to said other electrode is permitted.

55

12. In a transmitter, a casing, a pair of electrodes on the opposite sides of said casing, a third electrode located between the first mentioned electrodes, granular resistance material between said electrodes, a stem 60 passing through said box and carrying said third electrode, resilient connections between said stem and said casing, whereby a limited movement of said third electrode with respect to said other electrode is permitted, and means for adjusting said flexible connections to regulate the movement 65 between said electrodes.

13. In a transmitter, a casing, electrodes mounted on the opposite sides of said casing, a third electrode between said first mentioned electrodes, granular resistance material in said box and surrounding said third electrode, a stem passing through said casing on which said third electrode is mounted, 70 and flexible connections on opposite sides of said casing to said stem, whereby a limited movement of said stem with respect to said casing is permitted.

75 14. In a transmitter, a casing, electrodes mounted on the opposite sides of said casing, a third electrode between said first mentioned electrodes, granular resistance material in said box and surrounding said third electrode, a stem passing through said casing on which said third electrode is mounted, 80 flexible connections on opposite sides of said casing to said stem, whereby a limited movement of said stem with respect to said casing is permitted, and means for adjusting 85 said flexible connections to thereby regulate the amount of movement permitted between said third electrode and said casing.

Signed by me at Chicago, Illinois, this 22nd day of March, 1913.

JOHN J. COMER.
